UNITED STATES PATENT OFFICE.

JESSE DEWEY LEWIS, OF LOS ANGELES, CALIFORNIA, ASSIGNOR, BY DIRECT AND MESNE ASSIGNMENTS, TO SCOTT E. ALLEN, HAL D. RIVES, AND FRANK CARROLL, ALL OF LOS ANGELES, CALIFORNIA.

MEASURE.

1,347,465.

Specification of Letters Patent. Patented July 20, 1920.

Application filed February 3, 1919, Serial No. 274,798. Renewed January 9, 1920. Serial No. 350,478.

To all whom it may concern:

Be it known that I, JESSE DEWEY LEWIS, a citizen of the United States, residing at Los Angeles, in the county of Los Angeles and State of California, have invented a new and useful Measure, of which the following is a specification.

My invention relates to measures, of the type having a movable spout, being more particularly a measure for dispensing oils. Oils, particularly lubricating oils as commonly dispensed to autos at filling stations, are usually poured from a common measuring can through a funnel or tube into the engine. There have also been cans of this type made with swing spouts, but most of such cans are of expensive construction, and the principal object of my invention is to provide a measure of the character described, of simple form and construction, which may be cheaply produced and at the same time efficient in operation.

Other objects and advantages will appear hereinafter from the following specification.

Referring to the drawings, which are for illustrative purposes only,

Figure 1 is a side elevation of a measure partly in section showing a form embodying my invention.

Fig. 2 is an inverted plan view of the measure shown in Fig. 1, the same being shown on a reduced scale.

Fig. 3 is an enlarged vertical sectional view on line 3—3, Fig. 1.

Fig. 4 is a front elevation of the lower portion of the measure, and

Fig. 5 is a vertical sectional view on line 5—5, Fig. 3.

11 designates a can forming the body of the measure, said can having a handle 12 and a common form of pouring lip 13. The can is also provided with a foot rim 14, the front portion of which is cut away forming an opening 15 through which the spout projects as hereinafter more particularly described. The bottom 16 of the can is provided with an opening 17 through which the contents of the can are discharged into a valve casing 18, the lower end of which is closed by means of a circular plate or valve seat 19 having a discharge opening 20 there-

in, such opening 20 being substantially triangular in shape as indicated in dotted lines in Fig. 5.

Seated on the plate 19 is a sheet of felt or felt washer 21, the felt having an opening 22 therein of the same shape as the opening 21 in the plate 19 and registering therewith. The edge of the plate 19 is crimped over the edge of the felt as indicated at 23 for the purpose of securely holding the felt from movement on the plate 19 thereby insuring that the opening 22 in the felt registers at all times with the opening 20 in the plate 19. The edge of the plate 19 is also turned over against the edge of a disk 25 which disk constitutes the valve member which co-acts with the plate 19 to regulate the flow of oil from the valve casing 18 to the spout chamber, in the present form being conical in shape and formed by a conical member 26 soldered or secured in any suitable manner to the disk 25.

The disk 25 is provided with an opening 27 corresponding in shape to the opening 20 in the felt 19, such opening 27 being clearly illustrated in full lines in Fig. 5 of the drawing.

30 designates a spout which extends upwardly in front of the can 11, the upper end of the spout being curved outwardly under the lip 13 of the can and the lower end 31 of the spout extending horizontally inwardly through the opening 15 in the foot rim of the can and secured by solder or other suitable manner to the conical member 26, being in open communication therewith. To strengthen the construction of the valve casing, one edge 33 of the foot rim at the side of the opening 15 therein is bent inwardly as shown in Figs. 1 and 4 and soldered or secured in any suitable manner to the circular edge of the plate 19.

In use the can is filled with oil, the spout being in full line position shown in Fig. 1 in which position the opening 27 in the disk 25 is in the full line position shown in Fig. 5. When the can is to be emptied the spout is turned into the dotted line position in Fig. 1 which swings the disk 25 on the felt 21 so that the opening 27 in the disk 25 corresponds with the opening 20 in the plate 19, the contents of the can being discharged from the valve casing through

the openings 20 and 27 into the spout chamber 26 thence through the spout until the can is emptied.

By constructing the valve, that is, the spout chamber with its disk 25 and the valve casing with its plate 19 as above described, a very efficient valve is produced, of simple form and construction. The disk 25 working against the felt 21 insures that no leakage takes place from the valve casing to the spout chamber until the spout is moved to bring the opening 27 in the disk 25 to register with the opening in the plate 19.

By crimping the edge of the felt in the edge of the plate 19 as above described the felt is firmly held in place and the movement of the disk 25 against the felt does not dislodge the same or move it with relation to the plate 19. The felt washer is constantly lubricated from the oil passing through the valve which insures that the disk will not stick so that the spout can be readily turned at all times.

While I have described the washer 21 as being made of felt, it is understood that I do not limit myself to the use of such material but that cork, leather or a similar substance may be used for this purpose.

What I claim is:—

1. A measure comprising a can having an opening in the bottom, a valve casing in open communication with said opening, a plate formed on the valve casing, having a

discharge opening therein, a felt washer 35 against the said plate having a corresponding opening therein, said felt washer being crimped at its edge within the edge of the plate, a valve disk against said felt washer retained within the edge of the plate, said 40 disk having an opening therein, a spout chamber formed on said disk, and a spout in open communication with said spout chamber.

2. A measure comprising a can having an 45 opening in the bottom, a foot rim on the can for elevating the bottom of the can, said foot rim having an opening in the front thereof, a valve casing in open communication with the opening in the bottom of the 50 can and extending downwardly, a vertically arranged plate having a discharge outlet forming part of said casing, a felt washer against the plate having a corresponding opening therein, means for preventing 55 movement of the washer on the plate, a valve disk on said washer having an opening therein arranged to register with the opening in the plate when rotated on the washer, means for rotatably mounting the 60 disk on the washer, a spout chamber formed on said disk, and a spout formed on the spout chamber extending forwardly through the opening in the foot rim.

In testimony whereof I have hereunto set 65 my hand at Los Angeles, California, this 25th day of January, 1919.

JESSE DEWEY LEWIS.
